UNITED STATES PATENT OFFICE

HARVEY J. DENNEY, OF WESTLAKE, LOUISIANA

INSIDE PIPE CUTTER

Application filed July 18, 1930. Serial No. 468,869.

This invention relates to new and useful improvements in an inside pipe cutter. One object of the invention is to provide a pipe cutter embodying a body, having a cylinder therein, with radially movable cutters in bearings in the body and a mandrel fitted in the cylinder and operatively connected with the cutters and operative to project the cutters outwardly into cutting position or to withdraw said cutters, said mandrel being operable in one direction by a yieldable member to withdraw the cutters and in another direction by fluid pressure beneath the mandrel to actuate the cutters outwardly in cutting relation with the pipe to be severed, said cutter embodying also means operable by fluid pressure for anchoring the cutter in the pipe during the cutting operation.

Another object of the invention is to provide a device of the character described embodying means adapted to engage with the severed section whereby said section may be dislodged and withdrawn with the tool from the bore.

With the above and other objects in view this invention has particular relation to certain novel features of construction, operation and arrangement of parts an example of which is given in this specification and illustrated in the accompanying drawings, wherein:

Figures 1, 2 and 3 show vertical sectional view of upper intermediate and lower sections, respectively, of the cutting tool.

Figure 4 shows a cross sectional view taken on the line 4—4 of Figure 1.

Figure 5 shows a cross sectional view taken on the line 5—5 of Figure 3.

Figure 6 shows a vertical sectional view disclosing a modified form of the means for anchoring the cutter in the pipe to be cut.

Figure 7 shows a vertical sectional view of the pulling device adapted to be attached to the lower end of the cutting tool and anchoring means of Fig. 6, and

Figure 8 shows a sectional view thereof on the line 8—8 of Figure 7.

Referring now more particularly to the drawings wherein like numerals of reference

designate similar parts in each of the figures the numeral 1 designates the cutter body, which is tubular in form having the inside cylinder 2 with the radiating cutter bearings 3, radially disposed therein. Attached to 55 the upper end of the body there is an operating string of pipe 4. Fitted in the cylinder there is an elongated mandrel 5 whose lower end is fitted with suitable cup rings 6 which fit closely in the cylinder and form in effect, 60 a plunger. Screwed into the upper part of the cylinder there is a thimble 7 and within this thimble there is a coil spring 8 which is interposed between the outward end of the thimble and the upper end of the mandrel. 65 The end of the mandrel adjacent the spring carries a pin 9 which is surrounded by said spring. The mandrel is actuated in one direction by said spring and the other direction by fluid pressure, as hereinafter explained. 70 The lower end of the cylinder has the inwardly extending annular flange 10 against which the lower end of the plunger is adapted to abut. The mandrel has the external upwardly converging grooves 11 and 75 the bottom of these grooves have the lengthwise dovetailed tenons 12. There are the radial cutters 13 in the bearings whose inner ends have dovetailed mortises 14 which receive the corresponding tenons 12. The 80 body has the longitudinal channels 15 leading from the upper to the lower end thereof and which is arranged around the cylinder 2.

Attached to the lower end of the body 1 there is a tubular section 16 whose lower end is thickened inwardly forming the bearing 17 and the upper and lower internal annular shoulders 18, 19.

The numeral 20 designates a connecting 85 nipple whose upper end is reduced forming the tubular spindle 21 which extends up through the bearing 17 and screwed onto the upper end of the spindle is the nut 22 into which is threaded the gland 23. Interposed between the nut 22 and the shoulder 18 are the bearing rings 24. The reduction of the nipple 20 forms the external shoulders 25, 26 thereon, the former of which abuts the lower end of the section 16 and between the 90 95 100

shoulder 19 and 26 are the antifriction bearings 27.

Connected to the lower end of the nipple 20 there is a tubular body 28 having the cylinder 29 therein, in which is the reciprocable plunger 30 whose upper end is equipped with the cup rings 31 and connected to the lower end of the body 28 is a guide point 32 in which is located a coil spring 33 on which the plunger 30 is seated. The plunger 30 and the guide point 32 have the aligned axial channels 34, 35 through which fluid may be admitted into the pipe 36 to be pulled so as to wash out said pipe beneath the tool if necessary. The cylinder body 28 has the radial slots 37 through which the pipe engaging jaws 38 work.

The inner ends of these jaws have the dovetailed tenons 39 which work in corresponding upwardly diverging mortises 40 in the plunger 30.

In operation the cutting tool may be assembled as shown in Figures 1, 2 and 3 and let down into the pipe 36 to be cut, to the desired point and fluid under pressure may be forced down through the string 4 passing down through the channels 15 beneath the plunger 5. The fluid under pressure will operate to simultaneously force the plunger 5 upwardly, which in turn will operate to force the cutters 15 outwardly into engagement with the pipe, and to force the plunger 30 downwardly and carry the jaws 38 outwardly into engagement with said pipe. The cutting tool will thus be anchored against longitudinal movement relative to the pipe 36 during the cutting operation and the string 4 may then be rotated with the cutters 13 held against the pipe until the pipe has been severed by them. The pressure may then be relieved and the spring 8 will force the plunger 5 downwardly to withdraw the cutters 13 and the spring 33 will operate to elevate the plunger 30 to withdraw the jaws 38 from said pipe to permit the withdrawal of the tool. If desired a pipe puller such as shown in Figures 6 and 7, may be assembled with the cutter and the severed section may be engaged by said puller and withdrawn from the bore as the cutter is withdrawn. This pipe puller will now be described. It comprises a tubular body 41 and when the puller is employed the guide point 32 will be attached to the lower end of said body 41, as shown in Figure 7, and the upper end of the body 41 will be connected directly to the lower end of the body 28. The body 41 is tubular having the cylinder 42 therein, in which there is provided a spider 43 forming a support for the spring 35. Reciprocable in the cylinder 42 is the plunger 44 whose upper end is equipped with the cup rings 45 and this plunger 42 has an axial channel 46 therethrough from end to end to permit fluid to pass downwardly and out through the channel 35 into the pipe beneath.

The plunger 44 is seated on the spring 47 which is confined in the guide point 32. The body 41 has a plurality of downwardly flared faces 48 on which the pipe engaging jaws 49 are mounted to slide and these jaws have longitudinal bearings 50 on the guide rods 51. The upper ends of these rods are connected to the body 41 and their lower ends abut the upper end of the guide point 32. The outer surfaces of the jaws 49 are arcuate and toothed so as to engage the pipe 36 and their inner sides have the lengthwise tenons 52 which work through the oblong slots 53 in the body 41 and fit snugly in the mortises 54 of the plunger 44.

During the cutting operation the fluid under pressure will also operate against the plunger 44 to force it downwardly, which will operate to carry the jaws 49 outwardly against the pipe 36 and these will serve as an additional anchorage for holding the device against longitudinal movement in the pipe during the cutting operation. After the pipe has been severed and the pressure relieved as above explained the spring 47 will operate to elevate the plunger 44 and this will carry the jaws 49 upwardly and inwardly out of engagement with the pipe. The entire tool may then be elevated until the jaws 49 are located within the severed section, and pressure again applied which will operate as above described to carry the jaws 49 into engagement with the severed section and an upward pull may then be exerted through the operating string 4 to dislodge the said severed section and the same may then be pulled out.

If the severed section can not be pulled the pressure may be relieved and the device lowered to release the jaws 49 and the spring 47 will then operate to again elevate the plunger 44 and carry the jaws 49 upwardly and inwardly, as explained, out of engagement with the pipe, and the tool may then be withdrawn or relocated in the pipe to make another cut.

While I have shown what I now consider to be the preferred form of the invention it is obvious that mechanical changes may be made therein and equivalents substituted for the parts shown and I reserve the right to make such mechanical changes and substitutions as may be found desirable within the principle of the invention.

What I claim is:—

1. A device for cutting and removing pipe from a well bore comprising a tubular cutter body, outwardly movable cutters therein, an anchoring device having a swivelling connection with the body, outwardly movable anchoring jaws therein adapted to engage the pipe to anchor the cutting means against longitudinal movement in the pipe during cutting operations, separate means operably connected with the cutters and jaws, respectively, and adapted to be actuated, simul-

taneously, by fluid pressure to move the cutters and jaws outwardly into active position in engaging relation with the pipe, a pulling device connected to said anchoring device and embodying outwardly movable pipe pulling jaws, means operable by said pressure and effective to move said pulling jaws into active position in engagement with the pipe.

10 2. A device for cutting and removing pipe from a well bore comprising a tubular cutter body, outwardly movable cutters therein, an anchoring device having a swivelling connection with the body, outwardly movable anchoring jaws therein adapted to engage the pipe to anchor the cutting means against longitudinal movement in the pipe during cutting operations, separate means operably connected with the cutters and jaws, respectively, and adapted to be actuated, simultaneously, by fluid pressure to move the cutters and jaws outwardly into active position in engaging relation with the pipe, a pulling device connected to said anchoring device and embodying outwardly movable pipe pulling jaws, means operable by said pressure and effective to move said pulling jaws into active position in engagement with the pipe and yieldable means normally tending to withdraw said cutters and jaws into inactive position out of such engaging relation with the pipe.

30 3. A device for cutting and removing pipe from a well bore comprising a tubular cutter body, outwardly movable cutters therein, an anchoring device having a swivelling connection with the body, outwardly movable anchoring jaws therein adapted to engage the pipe to anchor the cutting means against longitudinal movement in the pipe during cutting operations, separate means operably connected with the cutters and jaws, respectively, and adapted to be actuated, simultaneously, by said pressure to move the cutters and jaws outwardly into active position in engaging relation with the pipe, a pulling device connected to said anchoring device and embodying outwardly movable pipe pulling jaws, means operable by said pressure and effective to move said pulling jaws into active position in engagement with the pipe, said cutting and removing device having a longitudinal fluid channel therethrough.

50 4. A device for cutting and removing pipe from a well bore comprising a cutter body, outwardly movable cutting means therein, an anchoring device having a swiveling connection with the body, outwardly movable anchoring means therein adapted to engage the pipe to anchor the cutting means against longitudinal movement in the pipe during cutting operations, separate means operably connected with the cutting means and anchoring means respectively and adapted to

be actuated simultaneously by fluid pressure to move the cutting means and anchoring means outwardly into active position in engaging relation with the pipe, a pulling device connected to said anchoring device and embodying outwardly movable pulling means, means operable by said pressure and effective to move said pulling means into active position in engagement with the pipe.

5 70 In testimony whereof I have signed my name to this specification.
